UNITED STATES PATENT OFFICE.

GUS JATKO, OF SEATTLE, WASHINGTON.

PAPER-HANGER'S PASTING-MACHINE.

1,122,122.

Specification of Letters Patent. Patented Dec. 22, 1914.

Application filed November 5, 1913. Serial No. 799,370.

To all whom it may concern:

Be it known that I, GUS JATKO, a citizen of the United States, residing at Seattle, in the county of King and State of Washington, have invented new and useful Improvements in Paper-Hangers' Pasting-Machines, of which the following is a specification.

This invention relates to paper hangers' pasting machines, the object in view being 10 to produce a practical machine of the class described by means of which the paper as it is drawn over a roll is pasted on one side thereof in readiness to hang upon a wall or ceiling, while at the same time the decorated 15 face of the paper is kept clean and free from paste thus adding materially to the appearance of the completed work.

A further object of the invention is to 20 produce a machine in which the paper handling rolls are bodily movable or adjustable relatively to the tank or reservoir in which the paste is placed, whereby the paper may be threaded through the machine while the mechanism is clear of the paste, 25 and whereby also the pasting roller may be submerged or dipped to any desired depth in the paste according to the level of the latter in the tank or reservoir.

A further object of the invention is to 30 provide a folding and detachable table for the convenience of the paper hanger; also means for measuring off the paper so that sections of any desired length may be quickly and readily withdrawn from the 35 main roll without requiring each piece or section of paper to be measured individually.

With the above and other objects in view, the invention consists in the construction, 40 combination and arrangement of parts, as will hereinafter be more fully described, illustrated and claimed.

In the accompanying drawings:—Figure 1 is a vertical cross section partly in elevation of a pasting machine embodying the present invention showing the parts in their operative or pasting position. Fig. 2 is a similar view showing the paper handling mechanism elevated with respect to the paste 50 reservoir or tank. Fig. 3 is a vertical longitudinal section through the machine with parts in elevation, showing the means for raising and lowering the paper handling mechanism and clamping the same at any 55 desired elevation. Fig. 4 is a detail cross section through one of the standards and

runners. Fig. 5 is a detail vertical section showing the relation of the measuring mechanism to one of the guide rollers. Fig. 6 is a vertical section taken at right angles 60 to Fig. 5 showing the measuring mechanism. Fig. 7 is a detail face view of the stationary dial.

The machine contemplated in this invention comprises a base 1 which is shown of 65 open rectangular form comprising the longitudinal bars 2 and the cross bars 3 connecting the same, said frame being mounted upon suitable rollers or casters 4 so that it may be readily moved from place to place. 70

Secured rigidly to and extending upwardly from the cross bars 3 are two parallel standards 5 forming guides as will hereinafter appear. Each of said standards is provided with a T-shaped base 6 at the bottom thereof which is fastened to one of the cross bars 3 by means of screws or their equivalent as shown.

7 designates a substantially semi-cylindrical paste reservoir or tank formed of sheet 80 metal and secured by means of supporting brackets 8 to the base frame 1, said tank being provided with a removable cover 9 which is substantially semi-cylindrical and formed of sheet metal the same as the tank 7. 85

Mounted to move up and down between the parallel standards 5 is a frame comprising the two head sections 10 each of which comprises an arched portion 11 and a reversely arched portion 12 formed integrally 90 with each other and provided with bearing openings 13 and 14 for a pair of guide rolls 15 and 16 arranged in spaced relation to each other and at points about equidistant from and at opposite sides of the plane of 95 the standards 5. Between the rolls 15 and 16 is a relatively large roll 17 which constitutes the pasting roll, said roll being journaled at 18 in the inverted arched portions 12 of the heads 10 above referred to. The 100 rolls 15, 16 and 17 are of suitable length to receive the full width of a roll of paper indicated at 19, the said roll of paper being mounted on a shaft 20 having end pintles 21 which are contained in open slots 22 in a 105 pair of supporting extensions or ears 23 on the heads 10. The paper indicated at 24 passes from the roll 19 downward on the outside of the guide roll 15 under said roll and thence upward over the pasting roll 17 110 after which the paper passes downwardly under the roll 16 and thence upwardly

where it may be grasped by the operator and withdrawn from the machine in a pasted condition, the rear side only of the paper coming in contact with the pasting roll 17 which is partly submerged in the paste, the level of which is indicated by the line 25. The head frames 10 are provided centrally thereof with upwardly extending runners 26 which are in the form of rectangular sleeves as shown in Fig. 4 surrounding the parallel standards 5 which act as guides along which the runners 26 travel in a vertical direction. Each of said runners is provided with outwardly extending parallel ears 27 between which is pivotally mounted at 28 a cam lever 29 provided with a handle 30. By means of the two handles located at opposite ends of the machine, the vertically movable frame carrying the rolls above referred to may be unclamped from the standards 5 and raised or lowered and after being brought to the desired position, the frame may be again clamped by means of the cam levers 29.

25 In connection with the primary guide roll 15, I employ a scraper or squeegee 31 which is movable by means of a hand lever 32 into and out of contact with the surface of the pasting roll 17 for the purpose of removing surplus paste therefrom before being brought into contact with the paper as it travels over in contact with said pasting roll. Two of such levers 32 are pivotally mounted at 33 on the oppositely located heads 10 of the vertically adjustable frame, the scraper or squeegee 31 extending practically the entire length of the pasting roll. One or both of said levers 32 is provided with a thumb latch lever 34 the latch of 40 which engages the teeth of a rack 35 for the purpose of holding the scraper or squeegee in its adjusted relation to the pasting roll. A similar pair of levers 36 are arranged at the opposite side of the machine and are 45 pivotally connected at 37 to the head frames and connected by a brush head 38 provided with paste spreading bristles 39 which work in contact with the pasted surface of the paper as the latter passes under the secondary guide roll 16. The levers 36 are, like the levers 32, held in an adjusted position by means of a thumb latch lever 40 the latch of which engages the teeth of a rack 41. The racks 35 and 41 are conveniently 50 formed integrally with the head frames 10 as shown in Fig. 1.

The standards 5 are connected at their upper ends by a pair of brackets 42 provided at their lower ends with sockets 43 into which the upper extremities of the standards 5 fit, whereby the brackets 42 may be detached from the standards 5 by merely lifting them out of place. The two brackets 42 are provided with horizontal top rails 65 44 to which is fastened a table embodying

a stationary section 45 and a hinged section 46, the hinged section 46 being adapted to be folded over upon the stationary section 45 for storage or transportation.

47 designates inclined braces between the 70 curved portions 42 and the horizontal portions 44 of the brackets. The projecting ends of the horizontal portions 44 of the brackets are supported by means of telescopic extension legs, each of said legs comprising an outer tubular section 48 and an inner tubular or solid section 49 provided with a supporting foot or flange 50 at the bottom thereof adapted to rest on the floor. 75

51 designates a binding screw for relatively fastening the two sections of each telescopic leg to prevent accidental collapse thereof. The upper section 48 of each telescopic leg is fastened to its respective bracket in any convenient manner. 80

The operative positions of the parts is illustrated in Fig. 1. In order to thread a new roll of paper through the machine, the vertically adjustable frame is elevated as shown in Fig. 2 so as to move the pasting 90 roll 17 upwardly out of the paste in the bottom of the tank 7. The paper is then carried under the roll 15 over the roll 17 and under the roll 16 after which the vertically adjustable frame is lowered until the pasting roll 17 is properly submerged in the paste. The operator then merely has to draw the paper through the machine which acts to apply a coat of paste to the back of the paper and then spread the paste evenly 95 all over the surface of the paper before it emerges from the machine. The machine thus avoids the use of a large and unwieldy table and renders it unnecessary for the paper hanger to carry such a table to the place 100 of operation.

The pasting machine hereinabove described may be made very compact and may easily be carried from place to place and readily moved according to the positions required in the room being papered and also easily trundled from one room to another. The paste is evenly applied to the paper without requiring the paper to be thumbed or handled by the operator thus keeping the 110 paper in a clean condition at all times thereby adding materially to the appearance of the finished work.

To still further add to the value and efficiency of the machine as a whole, I provide means for automatically measuring the lengths of paper as they are drawn through the machine. This mechanism is best illustrated in Figs. 5, 6 and 7 where it will be observed that the shaft 14 of the roll 16 is 115 provided at one end with a disk 52 having an outwardly extending crank pin 53 to which are connected the lower extremities of two pawls 54 and 55 held yieldingly by springs 56 and 57 in engagement with the 120 125 130

teeth of a ratchet wheel 58 journaled in a pair of oppositely located plates 59 forming the casing of the measuring mechanism. Fast on the same shaft 60 with the ratchet wheel 58 is an indicating hand 61 which travels around the graduated face of a dial 62. Therefore, when the roll 16 is turned by frictional contact of the paper passing around the same, the pawls 54 and 55 actuated the ratchet wheel 58 and turn the indicating hand 61 around the dial until it registers with the desired measurement indicated on the dial. The hand 61 is adapted to be turned backwardly by means of a thumb wheel 63 fast on the arbor or shaft 60 on which the ratchet wheel 58 is frictionally held. The wheel 58 will by reason of such frictional resistance cause the hand 61 to turn but the hand may be set back by over-coming said frictional resistance with the aid of the wheel 63.

What I claim is:—

1. A paper hanger's pasting machine comprising a supporting base, guiding standards extending upward therefrom, a paste reservoir supported by said base and open at the top, a vertically adjustable frame guided by said standards, means for raising and lowering said frame, a pasting roll journaled in said frame, paper guide rolls located at opposite sides of said pasting roll and adapted to direct the paper over the top of the pasting roll and in contact therewith, and a table detachably mounted on the upper ends of said standards.

2. A paper hanger's pasting machine comprising a supporting base, guiding standards extending upward therefrom, a paste reservoir supported by said base and open at the top, a vertically adjustable frame guided by said standards, means for

raising and lowering said frame, a pasting roll journaled in said frame, paper guide rolls located at opposite sides of said pasting roll and adapted to direct the paper over the top of the pasting roll and in contact therewith, and a table mounted on the upper ends of said standards and embodying a stationary section and a hinged and folding section. 45

3. A paper hanger's pasting machine comprising a supporting base, guiding standards extending upward therefrom, a paste reservoir supported by said base and open at the top, a vertically adjustable frame guided by said standards, means for raising and lowering said frame, a pasting roll journaled in said frame, paper guide rolls located at opposite sides of said pasting roll and adapted to direct the paper over the top of the pasting roll and in contact therewith, a table mounted on the upper ends of said standards, and extension legs supporting said table. 55

4. A paper hanger's pasting machine comprising a supporting base, outwardly guiding standards extending upward therefrom, a paste reservoir supported by said base and open at the top, a vertically adjustable frame guided by said standards, means for raising and lowering said frame, a pasting roll journaled in said frame, paper guide rolls located at opposite sides of said pasting roll and adapted to direct the paper over the top of the pasting roll and in contact therewith, and paper measuring mechanism actuated by one of the guide rolls. 70 75

In testimony whereof I affix my signature in presence of two witnesses.

GUS JATKO.
